UNITED STATES PATENT OFFICE.

CHESTER I. WAGNER, OF DAYTON, OHIO, ASSIGNEE TO THE SHAW-WALKER COMPANY,
OF MUSKEGON, MICHIGAN, A CORPORATION OF MICHIGAN.

INDEX.

1,111,931.

Specification of Letters Patent. Patented Sept. 23, 1913.

Application filed February 20, 1912. Serial No. 749,714.

To all whom it may concern:

Be it known that I, CHESTER I. WAGNER, a citizen of the United States, residing at Dayton, in the county of Montgomery and State of Ohio, have invented new and useful Improvements in Indexes, of which the following is a specification.

My present invention relates to indexes, and its object is to provide for indexes having removable indexed matter, an improved indicator adapted to be inserted into the index to mark the place therein from which such matter has been removed.

This object and others appearing herein-after are attained by, and my invention finds a preferable embodiment in, the structure hereinafter described and illustrated in the accompanying drawings, in which:—

Figure 1 is a view in perspective of an index applied to a filing system, and illustrating my improved indicator as used in connection therewith. Fig. 2 is a section of the indicator on line A—B of Fig. 1: and Fig. 3 shows a filled-in-blank form or requisition-record card adapted to be used as part of the indicator.

The filing system illustrated comprises containers or "folders" 1, each adapted to hold the papers relating to one subject, as the correspondence with one person, and properly distinguished, as by the name of such subject or person displayed on suitable tabs, as shown: These containers are arranged in alphabetical order, suitable guide cards 2 being provided, and the whole being contained in a suitable filing tray or drawer 3, indicated in broken lines; all of which being of ordinary and usual construction and arrangement.

In the construction illustrated, my indicators 4, 5, 6, 7, 8, (commonly called "out cards") have upwardly-projecting tabs each displaying the word "Out": When a folder is removed from the filing system, an indicator is inserted in its place; as for instance, the folder containing the correspondence of "T. A. Allen" having been removed, the out-card 4 replaces it; similarly, the out-card 5 indicates that the folder of "Barnes", has been removed, and so on. In like manner, if any part of the contents of the folder is withdrawn, an out-card is inserted in the filing system to indicate that fact. The tabs of these out-cards are arranged in different positions thereon as shown, in order to indicate

"attention dates", viz, the time the folder or its contents was removed, or when it should be returned, etc. The number of these different positions for the tabs may vary, of course, with the requirements of the particular indexing system to which my out-cards are applied: In the system illustrated, there are three positions for these tabs, the first position being shown in out-cards 4 and 7, the second position in out-cards 5 and 8 and the third in out-card 6: The tabs in first position may be adopted as indicating that their out-cards were inserted on Monday or Thursday; those in second position, that their out cards were placed in the system on Tuesday or Friday; while the third position tab would indicate the removal of the folder and insertion of the out-card on Wednesday or Saturday. Thus, attention is directed not only to removed folders, but also to their "attention dates" viz, the time of their removal, or to the time such folders should be returned.

My indicators, or out-cards, are adapted to removably hold a requisition or record card 9, 10, on which may be written merely the name of the folder removed, as in 9; or anything else desired; or on which may be printed any suitable blank form, as that illustrated in card 10 shown filled-in in Fig. 3. It will be seen that these requisition-order-cards, when preserved, form a permanent record of the withdrawals of the files in question; and that, by the use of such requisition-record cards, is obviated the necessity of writing on each folder, or the out card, the memorandum concerning each withdrawal.

The requisition-record-card may be held on the out card by various devices: preferably, however, by spring clips 11 fastened to the out-card as by tubular rivets 12 shown, and adapted to receive the requisition-record card and press it against the face of the out-card, each spring clip having an inwardly bent portion 13 between its attached and its free ends pressing on such requisition-record card.

Not confining myself to details of construction shown or described, I claim:—

1. In an index, a plurality of indicators adapted to be severally inserted into the respective places of withdrawn indexed matters having different attention dates, the indicators having distinctions in such

2
inter-relative position thereon as to severally suggest the corresponding attention dates of their respective withdrawn indexed matters.

5 2. In an index, a plurality of out-cards adapted to be severally inserted into the respective places of withdrawn indexed matters having different attention dates, the out-cards having tabs in such inter-relative lat-
10 erally arranged position thereon as to severally suggest the corresponding attention dates of their respective withdrawn indexed matters.

15 3. In an index, a plurality of out-cards adapted to be severally inserted into the respective places of withdrawn indexed matters having different attention dates, the out-cards having tabs in such inter-relative po-
20 sition thereon as to severally suggest the cor-
25 responding attention dates of their respective withdrawn indexed matters.

4. In an index, an out-card adapted to be inserted into the index in place of with-
25 drawn indexed matter, a card adapted to display memoranda relative to such with-

drawn matter, and means carried by the out-card for yieldingly enclasping the said card on the out-card.

5. In an index, an out-card adapted to be inserted into the index in place of withdrawn indexed matter and having a spring clip, and a card adapted to display memo-
30 randa relative to such withdrawn matter and to be removably held in the clip.

6. In an index, an out-card adapted to be inserted into the index in place of withdrawn indexed matter and having a spring clip, and a card adapted to display memo-
35 randa relative to such withdrawn matter and to be removably held by the clip, the middle portion of the clip being bent in-
wardly to engage with greater pressure the memoranda card near its middle portion.

In testimony whereof I have hereunto set
my hand in presence of two subscribing wit-
nesses.

CHESTER I. WAGNER.
